CLAIM

The ornamental design for a packaging container as shown and described.

DESCRIPTION

FIG. 1 is a perspective view of a packaging container, showing our new design.

FIG. 2 is a perspective view thereof showing the cap off.

FIG. 3 is a front view of FIG. 1 thereof.

FIG. 4 is a rear view thereof.

FIG. 5 is a top plan view thereof.

FIG. 6 is a bottom plan view thereof.

FIG. 7 is a right side view thereof.

FIG. 8 is a cross-sectional view taken along line **8-8** of FIG. 3 thereof.

FIG. 9 is an enlarged cross-sectional view taken along line **9-9** of FIG. 3 thereof.

FIG. 10 is an enlarged cross-sectional view taken along line **10-10** of FIG. 3 thereof.

FIG. 11 is a cross-sectional view taken along line **11-11** of FIG. 5 thereof.

FIG. 12 is a perspective view thereof showing that the gray part is transparent.

FIG. 13 a cross-sectional view taken along line **8-8** of FIG. 3 thereof showing that the gray part is transparent; and, FIG. 14 is an enlarged front view of the cap thereof without the transparent part.

A left side view is omitted because it appears symmetrical with the right side view.

The part corresponding to the gray part of FIG. 12 and FIG. 13 is transparent.
